UNITED STATES PATENT OFFICE.

CHARLES B. RUMSEY, OF HOMER, NEW YORK, ASSIGNOR TO THE NEW JERSEY WIRE CLOTH COMPANY, OF TRENTON, NEW JERSEY.

LOOM-REED.

SPECIFICATION forming part of Letters Patent No. 532,340, dated January 8, 1895.

Application filed February 2, 1894. Serial No. 498,908. (No model.)

To all whom it may concern:

Be it known that I, CHARLES B. RUMSEY, a citizen of the United States, residing at Homer, county of Cortland, and State of New York, have invented certain new and useful Improvements in Loom-Reeds, fully described and represented in the following specification and the accompanying drawings, forming a part of the same.

10 This invention relates especially to that class of looms used for weaving wire in making wire cloth, the reeds embodying the present invention being of special value as applied in such looms, although they may be 15 used in other classes of looms.

In wire looms the dents must be arranged so that the warp wires are positively guided on opposite sides, and lateral play of the wires prevented, while at the same time it is important that all irregularities in the wires caused by knots, bends, &c., shall not catch in the dents, as would be the case if the two guiding surfaces for the opposite sides of the wire were positioned directly opposite each 25 other and so close together as to furnish the desired positive guide of the wire. These results are secured in accordance with the present invention by using dents having their guiding portions equal in width to the thickness between two wires, so that the opposite sides of each dent shall form guiding surfaces for two adjacent wires and making these dents tapering and placed with their thickest portions, which form the guiding surfaces, 30 alternately at the front and rear of the reed and at a sufficient distance apart longitudinally of the warp to provide space for the easy passage of irregularities.

The form of the dents may be varied and 40 many of the advantages resulting from the invention be secured, but it will be found preferable to make the dents with rounded guiding surfaces which enable the reed to swing more readily over the wire and prevent 45 the catch of the dents on knots therein, and in the construction which I deem preferable the dents are made somewhat oval in cross section, thus tapering in both directions from the thickest or guiding portion and more 50 gradually on one side.

In the accompanying drawings forming a part of this specification, there are shown, for the purpose of illustration, constructions embodying the invention in the preferred forms, and a detailed description of the same will 55 now be given and the features forming the invention then specifically pointed out in the claims.

In the drawings—Figure 1 is a side view of a portion of a reed of the preferred form. 60 Fig. 2 is an enlarged cross section of the dents. Fig. 3 is a view similar to Fig. 2 showing a modification.

Referring now especially to Figs. 1 and 2, A is the reed frame, B the dents, and C the 65 wires. The dents B, as shown, are formed of bars approximately oval in cross section, providing rounded guiding portions and tapering in both directions from the thickest or guiding portions but tapering more gradually 70 in one direction than the other, forming a quicker taper or curved surfaces *l* on shorter radii and a slower taper or curved surfaces on longer radii and arranged alternately with their guiding portions at the front and rear 75 of the reed. The thickness of the guiding portions is equal to the distance between adjacent wires and the opposite sides of each dent form guiding surfaces for two adjacent wires. Thus the wires, while positively 80 guided against lateral play, have a freedom of movement between the dents to permit the passage of irregularities.

The dents may be made of any suitable width, that shown forming an efficient construction permitting irregularities to pass readily.

It will be seen that the edges of the dents at the front side of the reed form the beating up surfaces as usual. While these beating 90 up surfaces are wider apart than in reeds of the common forms, they will be found sufficient.

While the construction shown in Figs. 1 and 2 will be found very desirable as providing extended guiding surfaces, thus lessening the effect of wear and increasing the durability of the reed, it will be understood that this form may be varied without departing 95 from the invention. Thus, in Fig. 3, I have 100

shown a construction in which the blunt edges of the dents are circular and the tapering sides straight lines, but it will be seen that the guiding surfaces are reduced somewhat 5 from the oval form shown in Fig. 2.

- I do not claim herein broadly a loom reed having dents provided with guiding portions equal in thickness to the distance between adjacent warp strands, said guiding portions 10 being placed alternately at the front and rear of the reed, in combination with beating up surfaces at the front of the reed between the dents, but only such dents tapering from their guiding portions toward the opposite side of 15 reed, as defined by the claims, so that any beating up surfaces at the front of the reed between said guiding portions are formed on the dents themselves and not by bars separate therefrom.
- 20 What I claim is—
1. A loom reed having dents provided with guiding portions equal in thickness to the distance between adjacent warp strands, said guiding portions being placed alternately at 25 the front and rear of the reed and said dents

tapering to the opposite side of the reed, substantially as described.

2. A loom reed having dents provided with curved guiding portions equal in thickness to the distance between adjacent warp strands, 30 said guiding portions being placed alternately at the front and rear of the reed and said dents tapering toward the opposite side of the reed, substantially as described.

3. A loom reed having dents oval in cross 35 section and having their thickest or guiding portions alternately at the front and rear of the reed and equal in thickness to the distance between adjacent warp strands, the thinner portions of said dents forming beating up surfaces at the opposite side of the reed from the guiding portions substantially 40 as shown and described.

In testimony whereof I have hereunto set my hand in the presence of two subscribing 45 witnesses.

CHARLES B. RUMSEY.
